ATTORNEY

UNITED STATES PATENT OFFICE.

ROBERT J. ROGERS, OF YAKIMA, WASHINGTON.

BARREL-HANDLING DEVICE.

Application filed June 20, 1927. Serial No. 199,882.

This invention relates to barrel handling devices and has as one of its objects to provide a device that will eliminate the necessity of standing barrels on end preliminary to loading on a hand truck for movement from place to place.

Another object of the invention is to provide a barrel handling device whereby the barrel itself forms its own supporting and moving means.

A further object of the invention is to provide a barrel handling device that by utilizing the relatively large diameter of the barrel as the vehicle, as compared with a small diameter wheel of a truck, reduces to a minimum the friction.

A further object of the invention is to provide a barrel handling device equally efficient for forward or rearward propulsion.

A further object of the invention is to provide a barrel handling device that may be utilized as skids on steep inclines.

A further object of the invention is to provide a barrel handling device that is simple and cheap to manufacture, and that is highly efficient in its operation.

With this and other objects in view, reference is now had to the accompanying drawings in which

Fig. 1 is a plan view of the device, showing its application;

Fig. 2 is an end elevation of the device with part of the handle broken away, showing the position of adaptation to the barrel;

Fig. 3 is an end elevation showing the position of the device when pulling the barrel.

Fig. 4 is an end elevation showing the relative position of the device with an inclined plane; and

Fig. 5 is an elevation showing the device inverted and acting as skids.

Having reference to the drawings, like numerals refer to like parts throughout the several views, and the numeral 1 refers to a barrel, which may be of the drum variety as shown, wherein reinforcing bands 2 are placed about the drum, or of any cylindrically formed barrel or like package.

The device consists of a radially extending handle 3 comprising preferably a handle bar 4 and an extended member 5, the latter being attached to a cross member 6 with suitable braces 7 connecting the handle with other parts of the device, as the cross piece 8, the cross pieces in turn being attached to a claw 9 with which the handle is provided.

The claw 9 comprises a pair of members 10 positioned to partly encircle the barrel near either end thereof and are held in spaced parallel relation by the above mentioned cross 60 pieces and such others as may be necessary.

Each claw member is formed to a partial, or imperfect circle and comprises fingers 12 and 13 respectively having like curvature preferably, of different centers to space the 65 ends 14 of said fingers apart equaling the diameter of said barrel to provide for ease of mounting the device on the barrel, this action being shown in Fig. 2.

The fingers will be designated as forward 70 and rear fingers respectively, the forward fingers 12 being positioned on the opposite side of the barrel from the handle 3 and the rear fingers 13 being positioned on the same side of the barrel as the handle, the fingers 75 having a generally central juncture 15 formed at the meeting of the forward and rear fingers and due to the different centers.

The claw is made frictionless by attaching rollers thereto, one main roller 16 to the central juncture, and the forward roller 17 and the rear roller 18 to the respective ends of the forward and rear fingers.

The rollers obviously are rotatable on the fingers and by their position, as above described, the main roller 16, positioned at the juncture point, will always contact the perimeter of the barrel, while the respective forward and rear rollers will contact the barrel one at a time, depending upon the direction 90 of propulsion, the forward roller 17 engaging the barrel as the barrel is propelled in the direction of the handle, at which time the rear roller 18 will be free, or conversely as the barrel is held in restraint in going down 95 a slight incline ahead of the handle.

It will now be noted that with the respective rollers in contact with the barrel that the fingers carrying these particular rollers will be maintained concentric with the perimeter thereof, and this fact is taken advantage of where the barrel is to be moved down a relatively steep incline, as shown in Fig. 5, the handle then being brought over the barrel to invert the fingers, which converts the forward fingers into skids, thus preventing 100 too rapid a descent.

This inverted position also permits of ease of movement of the device from or to the work, where the floor is rough or contains 110 large cracks.

In use the device is placed over the barrel

and the barrel is then moved to its destination by means of the handle the operator either pushing or pulling as may be required.

Where barrels are of the larger size it requires two men to raise them upon their end preparatory to getting them upon a truck for movement from place to place, and once mounted on the truck it is necessary to balance the barrel on the axle of the wheel of the truck, all this requiring exceptional muscular effort, while this device supports no load, the barrel carrying its own load and resting on the ground, and hence the power required is only that which is necessary to overcome the inertia and to keep the barrel in motion, which, with the natural friction being removed by the rollers, and eliminating the necessity of lifting the barrel up on end, reduces the labor incident to moving to a minimum.

By referring to Fig. 4 and noting the angle of the handle with respect to the handle shown in Fig. 3 it will be noted that the handle in Fig. 4 has the same relative inclination with that of Fig. 3 as the inclined plane bears to the horizontal plane of that figure, and also that the forward and rear rollers bear the same relationship to the plane on which the barrel is being moved, hence it becomes obvious that, regardless of the angle of inclination, there is no danger of either roller at any time coming in contact with the surface on which the barrel is moved which might interfere with the operation of the de-

vice, should either roller encounter a rough floor. This also accentuates the preference of the larger diameter of the barrel over that of the small wheel of the truck.

Having thus described my invention, I claim:

1. In a barrel handling device, a radially extending handle, cross members carrying braces secured to said handle, a pair of members rigidly secured to said cross members and formed and positioned to encircle each end of said barrel, each of said members terminating in identical oppositely positioned fingers adapted to receive and engage the barrel, and said members and said fingers providing a skid and supporting means for the barrel when inverted.

2. In a barrel handling device, a radially extending handle, cross members carrying braces secured to said handle, a pair of members rigidly secured to said cross members and formed and positioned to encircle each end of said barrel, each of said members terminating in identical oppositely positioned fingers adapted to receive and engage the barrel, friction rollers mounted in aligned relation in said fingers and said pair of members, and said members and said fingers providing a skid and supporting means for the barrel when inverted.

In testimony whereof I have affixed my signature.

ROBERT J. ROGERS.
